Primary Examiner — Khawaja Anwar*Assistant Examiner* — Mojtaba Tehrani(74) *Attorney, Agent, or Firm* — Michael A. Mochinski(57) **CLAIM**

I claim the ornamental design for a target hanger, as shown and described.

DESCRIPTION

FIG. 1 is a right side perspective view of a target hanger showing my new design;

FIG. 2 is a front elevational view thereof;

FIG. 3 is a back elevational view thereof;

FIG. 4 is a left side elevational thereof;

FIG. 5 is a right side elevational view thereof;

FIG. 6 is a top plan view thereof;

FIG. 7 is a bottom plan view thereof;

FIG. 8 is a cross sectional view thereof taken along line 8-8 of FIG. 4;

FIG. 9 is a cross sectional view thereof taken along line 9-9 of FIG. 2; and,

FIG. 10 is a right side perspective view thereof shown equipped with a target plate and being positioned above a T-post.

The ornamental design which is claimed is shown in solid lines in the drawings: The broken lines showing representation of the target plate and T-post in FIG. 10 is for illustrative purposes only and forms no part of the claimed design.
